UNITED STATES PATENT OFFICE

2,312,090

ADJUSTABLE WRENCH

Fred Gorrell, Odessa, Tex.

Application December 12, 1941, Serial No. 422,748

1 Claim. (Cl. 81—108)

The principal object of the present invention is to provide an adjustable wrench which has as its primary object the provision of means whereby the handle or shank of the wrench is used as the adjusting medium.

Another important object of the invention is to provide an adjustable wrench wherein the adjustable jaw thereof can be adjusted in a much more convenient and quick manner than is now permissible in conventional wrenches.

Other important objects and advantages of the invention will become apparent to the reader of the following description.

In the drawings:

Figure 1 represents a side elevational view of the improved wrench.

Figure 2 is an enlarged fragmentary side elevational view of the head portion of the wrench with parts in section.

Figure 3 is a cross section on the line 3—3 of Figure 2.

Figure 4 is a cross section on the line 4—4 of Figure 2.

Figure 5 is a side elevational view and section of the fixed inner jaw.

Figure 6 is a top plan view of the fixed inner jaw.

Figure 7 is a back elevational view of the adjustable outer jaw.

Figure 8 is a section on the line 8—8 of Figure 2.

Figure 9 is a section on the line 9—9 of Figure 2.

Referring to the drawings wherein like numerals designate like parts, it can be seen that the invention broadly comprises an outer jaw A, which is adjustable, a fixed inner jaw B and a rotary hand bar C for use in adjusting the jaw A with respect to the jaw B.

In carrying out the present invention, it can be seen that the outer jaw A has an elongated shank 5 formed with a transverse slot 6 at the inner end thereof. This end of the shank 5 is disposed between ears 7 on a collar 8, and a pin 9 is disposed through the ears 7 and through the slot 6. Thus the shank 5 is loosely connected to the collar 8. The back edge of the shank 5 is formed with a plurality of recesses 10 equidistantly spaced along the said shank.

The hand bar C has a knob 11 at its butt end, adjacent to which the bar is formed with a hanger hook opening 12.

A hand grip area is defined on the bar C by a plurality of longitudinally extending grooves 13 adjacent the collar 8. The presence of these

grooves of course facilitate rotation of the bar C when adjustment of the outer jaw A is desired.

The remaining end of the bar C carries the inner jaw B and for a distance inwardly of the bar C from the jaw B and terminating at the grooves 13, the bar is formed to provide a screw 15. The collar 8 being internally threaded receives the threads of the screw 15.

The inner fixed jaw B is formed with a longitudinally extending bore 16 for receiving a smooth pin extension 17 of the hand bar C. The terminal portion of this pin extension 17 is formed with a circumferential groove 18 which receives a pair of pins 19, 19 extending transversely through the block 20 of the inner jaw B in parallel relation with respect to each other (see Figures 2 and 3). Thus the inner jaw B is swivelly connected to the hand bar C.

A guideway 21 is provided for the shank 5 of the outer jaw A, the outermost portion of this guideway 21 being formed with a hand engageable knob 22. The outer portion of the guideway 21 carries a pair of hollow plugs 23, 24 threadedly disposed into the guideway and each has therein a compression spring 25 exerting force against a detent element 26.

It will be observed that a strip spring 27 is employed and carried by the inner jaw B to exert force against the shank 5 of the outer jaw A to maintain the outer edge thereof firmly against the outer portion of the guideway 21 and to the end that at all times one of the detents 26 will be engaged in one of the recesses 10. The distance between a pair of recesses 10 is less than the distance between the detents 26 so that only one detent is engaging in a recess 10 at any particular time.

It can be seen that the jaw B has upstanding flange portions 30 formed with openings 31 to receive a pin 32 which is disposed through a removable jaw piece 33 in opposed relation to gripping corrugations 34 formed on the outer jaw A.

It can now be seen, that in order to adjust the outer jaw A with respect to the inner jaw B, the grooved portion 13 of the hand bar C can be gripped and the hand bar rotated. This will result in the feeding of the collar 8 which by way of the shank 5 will force the jaw A outwardly or inwardly with respect to the said jaw B and the detent 26 will engage in the recesses 10 in order to prevent any likelihood of self-adjustment as the wrench is used on work.

While the foregoing specification sets forth the invention in specific terms, it is to be understood that numerous changes in the shape, size and

materials may be resorted to without departing from the spirit and scope of the invention as claimed hereinafter.

Having described the invention, what is claimed as new is:

A wrench comprising an outer jaw provided with a shank, an inner jaw provided with a guide for the shank, an internally threaded collar to which the inner end of the shank of the outer jaw is pivotally secured, a rotary handle provided with a threaded portion, threadedly dis-

posed through the collar and a swivelled connection between the threaded end of the rotary handle and the inner jaw, detent means between the guide and the shank on one side of the shank, said detent means consisting of a plurality of recesses formed in the shank and a spring projected element on the guide for projection into any one of the recesses, and a bowed spring fixed in said guide on the opposite side of the shank and bearing against said side.

FRED GORRELL.
